UNITED STATES PATENT OFFICE.

KENNETH W. CONOVER, OF BELMAR, NEW JERSEY, ASSIGNOR TO EDWARD H. THOMSON, OF BRADLEY BEACH, NEW JERSEY.

SNOWPLOW.

Application filed January 10, 1923. Serial No. 611,906.

To all whom it may concern:

Be it known that I, KENNETH W. CONOVER, a citizen of the United States, residing at Belmar, in the county of Monmouth and 5 State of New Jersey, have invented certain new and useful Improvements in Snowplows, of which the following is a specification.

This invention relates to snow plows and 10 has for one object the provision of a snow plow which may be driven in advance of a tractor or other propelling means, and another object of the invention is to provide a plow of compact form which will permit its 15 use on narrow roads and which will eliminate excess weight without any loss of efficiency. Another object of the invention is to provide a snow plow having side members which may be easily adjusted so as to determine 20 the width of the path to be formed and set to correspond to the quantity of snow which is to be removed, and a still further object of the invention is to provide a snow plow of such form that it will readily penetrate 25 a body of snow and turn aside the same without being subjected to the direct resistance of the snow. These several stated objects, and other objects which will appear incidentally in the course of the following 30 description, are attained in such a mechanism as is illustrated in the accompanying drawings, and the invention resides in certain novel features which will be particularly pointed out in the appended claims.

35 In the drawings, which illustrate one embodiment of the invention,

Figure 1 is a perspective view of my improved snow plow coupled to a tractor;

Fig. 2 is a view partly in longitudinal 40 section and partly in elevation;

Fig. 3 is a plan view of the plow;

Fig. 4 is an enlarged side elevation of the front runner and its mounting;

Fig. 5 is a view, partly in transverse section and partly in end elevation, of the said runner and its mounting;

Fig. 6 is a detail section of adjusting means employed in the plow;

Fig. 7 is a plan view of the parts shown 50 in Fig. 6;

Fig. 8 is an enlarged detail horizontal section through the front end of the plow;

Fig. 9 is a detail transverse section showing the rear runner, and

Fig. 10 is a detail elevation of the rear 55 runner.

In carrying out my invention, I employ a point 1 which is of a general triangular form in horizontal section and comprises diverging side plates, as shown most clearly in 60 Fig. 8, the said point extending downwardly and forwardly on a curved line, as shown most clearly in Figs. 1 and 2, whereby it is adapted to penetrate the body of the snow below the top of the same and tend to lift 65 and push aside the snow without being forced directly and abruptly against the same in opposition to the direct resistance offered by the snow. The upper and lower ends of the point are closed, as shown clearly 70 in Figs. 1, 2 and 3, so that the lower end of the point will have a sufficiently firm bearing upon the lower portion of the banked snow to avoid sinking into the same and the upper end of the point will offer a certain 75 measure of protection to the elements connected therewith to prevent excessive accumulation of loose snow on said elements to interfere with the proper adjustment of the plow. Extending rearwardly from the rear 80 side of the point and preferably formed integral therewith is a plate or bracket 5 having a short standard 14 secured thereto, said standard depending below the said plate or bracket and having a runner 15 pivoted to 85 its lower end. As shown most clearly in Figs. 4 and 5, the standard or post 14 is secured to the plate or bracket 5 by a plurality of bolts inserted through vertically spaced openings in the bracket and the upper end 90 of the post so that, by engaging the bolts or rivets in the proper openings, the runner may be set at a greater or less distance from the lower end of the bracket and the height at which the point of the plow will work 95 thereby regulated.

I also employ a pair of wings or blades 3 which have their front ends disposed between the side members of the point and constructed with slots 7 through which are 100 engaged curved rods or bolts 6, the ends of said rods or bolts projecting through openings provided therefor in the side members of the point and being fitted with securing nuts turned home against the said side members, this construction tending to prevent spreading of the side members of the point and also furnishing a hinged or movable 105

connection between the wings or blades and the point to permit the wings or blades to be adjusted to the work to be performed. As shown most clearly in Fig. 3, the wings 5 or blades diverge rearwardly from the point along curved lines, and they are dished vertically so that their upper edge portions project laterally and overhang their lower edge portions whereby, as the plow is forced 10 through the body of snow, the snow will be raised, deflected and rolled over to the sides so that the power required to propel the plow will be much less than is the case where the blades have flat vertical walls and are 15 subjected to the direct resistance offered by the bank of snow. On the inner sides of the blades or wings 3 are provided brackets 2 disposed vertically and arranged at such intervals as may be desired, the present illustration showing a bracket adjacent the front extremity of each blade, another bracket at the center thereof and a third bracket at the rear end thereof. These brackets may be formed integral with the 20 blades or may be rigidly secured thereto by any convenient means. They serve to reinforce the blades so as to minimize the tendency of the same to buckle under stress and also constitute bases or anchoring members 25 for blade-adjusting devices. Disposed midway between the blades and extending longitudinally of the plow is a frame 8 which may be constructed of angle iron or channel bars having their forward portions converging 30 and their front extremities rigidly secured to the rear end of the plate or bracket 5. The rear portions of the angle bars or channel irons extend rearwardly beyond the plow and may be rigidly secured to a tractor 35 or other propelling medium. A cross bar or beam 17 is secured rigidly to and extends between the side members of the frame 8 at the rear extremity of the forwardly converging portions thereof, and crossed diagonally extending braces 18 are 40 rigidly secured to the said forwardly converging portions so that a very rigid strong and substantial frame is produced. Upon the cross bar or beam 17 and the side members 45 of the frame 8 are secured guide brackets or loops 11 having central raised portions, through which may be extended bars 4 forming a part of and projecting inwardly from yokes which are rigidly secured to 50 the rearmost brackets 2 or similar bars 9 extending from the intermediate brackets 2. The bars 4 and 9 are provided with longitudinal series of openings 16, through which and an opening provided in the central portion of the loops or keepers 11 pins 10 are 55 inserted to retain the bars in any position in which they may be set.

To the lower ends of the rearmost brackets 2, I secure runners 13 which may be of any suitable form and are illustrated as

spherical knobs or terminals at the lower ends of attaching members which may be secured to the said brackets. As shown in Figs. 9 and 10, the runners are secured to the brackets by a plurality of bolts inserted through registering openings in the overlapping members so that, by fitting the bolts in the proper openings, the runners may be adjusted vertically to some extent and the lower edges of the blades or wings thereby 75 set at any desired height.

My plow is intended more particularly to be secured to a tractor and driven in advance of the same, as illustrated in Fig. 1, but other forms of propulsion may be employed. As the plow progresses, the point of the same will enter the body of snow below the surface of the same and will readily penetrate the snow inasmuch as the point is so formed that its lower end is appreciably in advance of its upper end and the forward edge of the point follows a parabolic curve so that, as the plow progresses, it will tend to lift and cut through the snow instead of merely pushing it aside. The blades or wings diverge gradually rearwardly from the point so that they will readily follow the point as it penetrates the snow and will easily deflect the snow to form a path of the desired width inasmuch as they are not driven abruptly against the snow but will act upon it in the same manner that the point acts thereon so that, in the use of the plow, there is a constant lifting and rolling over of the snow whereby it will be easily turned aside. The runners support the plow in such manner that it may move readily over the road bed so that excessive frictional resistance to its progress is eliminated and wear upon the lower ends of the point and the wings is minimized. The connections between the blades and the central supporting frame effectually braces the blades while at the same time permitting sufficient adjustment of the blades to permit the formation of a path of desired width. It will be readily noted also that the forward end of the supporting frame is connected with the point so that the direct thrust upon the point is opposed to the entire strength of the frame and the advance of the plow rendered easy. The compact form of my snow plow not only enables it to be driven by the expenditure of a minimum power but adapts the device to use on surfaces where weight is undesirable, such as side walks, private drives, lawns, etc. It may be very easily driven around corners or turned to make a second path at the side of a previously formed path, traveling in the opposite direction.

It is to be understood that, while I have illustrated one embodiment of my invention in the accompanying drawings, the drawings are to be considered as illustrative only.

and not restrictive, as various modifications in the minor details of construction may be made without involving any departure from the spirit or scope of the invention as the 5 same is defined in the following claims.

Having thus described the invention, what is claimed as new is:

1. A snow plow including a frame, a point rigidly mounted thereon and having 10 diverging side members, bracing means extending transversely between the side members, side wings extending at their forward ends between said side members and pivoted directly to said bracing means to be 15 swingingly connected with the point thereby, and means coacting between the side wings and the frame for adjustably spreading said wings.

2. A snow plow including a frame, a point rigidly mounted thereon and having 20 diverging side members, arcuately curved bracing means extending between said side members, side wings apertured to accommodate said bracing means and swingingly 25 connected with the point by said means, and means coacting between the side wings and the frame for adjustably spreading said wings.

3. A snow plow including a frame, a point rigidly mounted thereon and having 30 diverging side members, bolts extending between the side members bracing said members, side wings apertured to accommodate

said bolts and swingingly connected with the point by the bolts, and means coacting 35 between the side wings and the frame for adjustably spreading the wings.

4. A snow plow including a frame, a point rigidly mounted thereon, side wings swingingly connected with the point to extend 40 at opposite sides of the frame, means coacting between the wings near their rear ends and the frame for adjustably spreading the wings as well as rigidly supporting the rear ends of the wings with respect to 45 the frame, and means coacting between the intermediate portions of the wings and the frame rigidly supporting the wings medially.

5. A snow plow including a frame, a point 50 rigidly mounted thereon, side wings swingingly connected with the point to extend at opposite sides of the frame, vertically disposed plates extending transversely of the wings near their inner ends, keepers mounted upon the frame, yokes connected at their ends to the end portions of said plates and provided with bars extending freely through said keepers, and locking pins extending through the keepers and through 55 said bars rigidly securing the rear ends of the wings in spaced relation.

In testimony whereof I affix my signature.

KENNETH W. CONOVER. [L. s.]
